Patented September 6, 1904.

UNITED STATES PATENT OFFICE.

JAMES A. CARROLL, OF CAMDEN, NEW JERSEY.

DESIGN FOR A RUG.

SPECIFICATION forming part of Design No. 37,122, dated September 6, 1904.

Application filed August 9, 1904. Serial No. 220,124. Term of patent 3½ years.

To all whom it may concern:

Be it known that I, JAMES A. CARROLL, a citizen of the United States, and a resident of the city and county of Camden, State of New Jersey, have invented a certain new, original, and ornamental Design for a Rug, of which the following is a specification, reference being had to the accompanying drawing, forming a part thereof.

10 The design therein represented relates to the surface ornamentation of a woven rug.

The drawing shows one corner of the rug, the other parts not shown being a duplicate of the parts shown.

I claim—

15 The ornamental design for a rug as shown.

JAMES A. CARROLL.
